UNITED STATES PATENT OFFICE.

GEBHARD JAEGER, OF COLUMBUS, OHIO.

CONCRETE-MIXER.

1,390,442.

Specification of Letters Patent. Patented Sept. 13, 1921.

Application filed November 28, 1919. Serial No. 341,028.

To all whom it may concern:

Be it known that I, GEBHARD JAEGER, a citizen of the United States, residing at Columbus, in the county of Franklin and State of Ohio, have invented a certain new and useful Improvement in Concrete-Mixers, of which the following is a specification.

Portable concrete machines of the type having a single opening for the feed and discharge usually have their mixing vessels set as low as possible and are mounted upon wheels. The primary receiver or bucket for the materials to be mixed rests on the ground so that the materials can be conveniently shoveled or discharged from a wagon thereinto. Consequently the ground position of the primary receiver is somewhat remote from the mixing vessel and the problem is to bring the low-lying primary receiver to the mouth of the mixing vessel without raising the same to an undue height and to effect quick discharge of the contents of the primary receiver into the mixing vessel.

This problem I have solved generally by hingedly connecting the primary receiver to an intermediate frame, hingedly connecting said frame to the mixer frame and providing means for raising the primary receiver and the intermediate frame together and then the primary receiver alone to the discharging position.

An example of the invention is shown in the accompanying drawings and set forth in the following specification, the features of novelty being finally claimed.

In the said drawing—

Figure 1 is an end elevation of the machine showing the primary receiver in its lowered position.

Fig. 2 is a similar view showing the primary receiver raised to the position where it is discharged into the mixer.

Fig. 3 is a side view of the apparatus with the bucket omitted.

Fig. 4 is mainly a plan view looking down from the line IV—IV Fig. 1.

In the views 5 designates the mixing vessel which is pivoted at 5^a to swing in a suitable frame 6 mounted on a wheel truck 7. Such a mixing vessel 5 usually has mechanism for revolving it unnecessary here to be particularly shown or described.

8 designates the bucket or primary receiver. This bucket is hinged at 9 to a frame 10, prismatic in form with triangu-

lar ends, said frame being hinged at 11 to a supplemental frame 6^a secured to the frame 6 so that the frame 10 with the bucket 8 are capable of being swung as a unit up and down on the hinge 11, and the bucket capable of an independent swinging movement upon the hinge 9. In a general way the frame 10 constitutes a link connecting the bucket with the main mixer frame. 65

To operate the bucket or receiver 8 and the intermediate frame 10 there is attached to each of its opposite sides a cable 12 running over a pulley 14 to a windlass 15, the latter being operated by suitable power. 70

A spring 16 connecting the bucket with the frame 10 tends to hold the bucket against said frame thereby preventing much noise in operation.

In practice the empty mixing vessel is 75 turned on its pivot 5^a to the position shown in Fig. 1.

After supplying the bucket with the materials to be mixed the bucket and frame 10 are raised together by properly operating the windlass until the upper face of the frame 10 (as shown in Fig. 1) strikes the supplemental frame 6^a and is arrested thereby after which the bucket goes alone to the position shown in Fig. 2. In this operation 80 the nose of the bucket is projected into the mouth of the bucket and the side of the bucket serves as a chute at a steep inclination to discharge the contents into the mixing vessel 5. It may be observed that if the 90 bucket 8 and intermediate frame 10 were made as one rigidly connected structure hinged at 11 the intermediate frame would collide with the rim of the mixing vessel 5 and prevent the desired steep inclination 95 and rapid discharge of the bucket.

The spring 12 also aids in holding the bucket against the frame 10 so that in the first portion of the lifting operation the two parts will turn on the hinge 11 and not on 100 the hinge 9.

The forms of the parts can be changed without departing from the gist of the invention as claimed.

What I claim is:

1. The combination with a mixing vessel, a frame for supporting the same, of a bucket for the materials to be mixed, a link hingedly connected with both the bucket and frame, means for elevating both the bucket 110 and the link, and means for arresting the upward movement of the link when the

- bucket and the link are raised without arresting the upward movement of the bucket.
2. The combination with a mixing vessel, a frame for supporting the same and a bucket for the materials to be mixed, of an intermediate frame of substantially right triangular prismatic form hinged along one of its acute angled corners to the mixer supporting frame with its right angled corner
- 5 10 uppermost when the prismatic frame is in lowered position and to which the intermediate frame the bucket is hinged along its right angled corner, means for elevating said bucket and intermediate frame, and

means whereby the intermediate frame is arrested in its upward movement without arresting the upward movement of the bucket, substantially as described.

3. In combination with a mixing vessel, its frame, and a bucket for the materials to be mixed, of an intermediate frame hinged to the mixer frame and to which the bucket is hinged, a spring connecting the bucket and intermediate frame and tending to hold the bucket against said intermediate frame, and means for raising said bucket and intermediate frame, substantially as described.

GEBHARD JAEGER.
